STEPLADDER

William Mumbrauer, New York, N. Y.

Application February 12, 1942, Serial No. 430,545

3 Claims. (Cl. 228—67)

My invention relates to improvements in stepladders or stands and similar devices, and it is the principal object of the invention to provide a safety device for the ladders to prevent a person, for instance one standing upon the uppermost step or platform, from falling forward while working, thus protecting the same against injury and possible death by such a fall.

Another object of my invention is the provision of a stepladder which, when not in use, may readily be collapsed for storage purposes while the safety device is locked parallel to the ladder legs so as to present a smooth exterior face.

Still another object of the invention is to provide a stepladder with a safety device or guard which can readily be swung from its lowered position into its upright working position and locked therein to act as a guard.

A further object of my invention is the provision of a collapsible stepladder of comparatively simple and inexpensive construction, yet durable and highly efficient in its operation.

A still further object of my invention is the provision of a stepladder in which the safety device is equipped with a platform which in the lowered position of the guard serves as a locking member, while in the elevated position it is directly in front of the operator for supporting tools, pails, etc.

The stepladder according to my invention extends by the provision of its safety device, the use of the ladder as such as it permits the full use of all rungs up to the upper platform, and the convenient locking and unlocking of the safety device in its upright as well as in its collapsed position.

Other objects of the invention will become apparent as the description proceeds, and will then be defined in the claims.

In the accompanying drawing forming a material part of this disclosure:

Fig. 1 is a rear elevation of a stepladder constructed according to my invention.

Fig. 2 is a fragmentary side elevation of the ladder partly in section on line 2—2 of Fig. 1.

Fig. 3 is a fragmentary side elevation of the stepladder with the safety device thereof in its elevated working position.

As illustrated, the usual stepladder 10 of the collapsible type comprises the pairwise arranged, parallel legs 11 connected by the rungs 13 at certain intervals, supported at their ends by the usual cleats. The upper ends of the legs 11, 12 are secured to the side boards 14 on their outside and carry the platform 15. To a transverse rod

16 resting with its ends in suitable bearings in the rear ends of the side boards 14 are movably secured the upper ends of the also pairwise arranged rear legs 17, 18 connected at certain intervals by braces 19, 20 and 21.

The novel safety device or guard according to my invention comprises a member, generally designated 22 hingedly secured, as at 23, 24, to the rear face of the upper base 21. Intermediate its ends near the lower end of its upper, substantially square part, the member 22 has pivotally attached thereto the angular ends of a loop 25 or the like for a purpose hereafter more fully described. The lower, forked end of the member 22 carries an inwardly directed plate 26 engaging in its lowered position with its somewhat curved auxiliary member 27 the lower end of a spring controlled latch 28 in a casing 29 on the inner face of the lower brace 19. If swung about its hinges 23, 24, the protecting member 22 will assume the upright position indicated in Figure 3 where the plate 26 serves as a support for pails, bulbs or other work-pieces, and in this position the loop 25 engages the inner face of a member 30 secured to the edge of platform 15, and said member 30 has a median spaced body to allow the release of the loop by the fingers if it is desired to swing the member 22 into its lowered position of rest indicated in Fig. 2. The pairs of legs 11, 12 and 17, 18 are connected by segments 32 having arcuate slots 33 in which travel screws when it is desired to collapse the stepladder and store it. These screws are normally securing the ends of the segments 32 near their slots to the respective legs.

In operation, the lower end of the member 22 is gripped to release the engagement between plate 26 and its member 27 with the spring latch 28 whereupon the member 22 is swung about its hinges 23, 24 into its upright position illustrated in Fig. 3. If now the loop 25 is swung about its pivots 34, it will engage the outer face of the ladder member 30 and securely lock the member 22 in its upright position to protect a person standing on the uppermost step or platform 15 from falling forward while engaged in using tools or other paraphernalia necessary to perform any work at hand. Upon release of the loop by means of fingers operating in the recess 31 of said member 30, the member 22 can then be turned about its hinges to assume the downward directed position parallel to the legs and the plate 26 will repress the latch by its member 27 whereupon the latch will be pressed by its spring to engage the platform 26 behind member 27 and thus

lock the member 22 in its lowered position, and the pairs of legs can now be collapsed in the usual manner.

It will be understood that I have described and shown in the preferred form of my stepladder as one example only of the many possible ways to practically construct the same, and that I may make such changes in its general arrangement and in the construction of its minor details as come within the scope of the appended claims without departure from the spirit of my invention and the principles involved.

Having thus described my invention, what I claim as new, and desire to secure by Letters Patent is:

1. In a stepladder as described a flat member hingedly secured at one end to one of the stepladder members, a platform at the opposite end of said flat member constituting part of a locking means, inwardly extending in the inoperative position of the said member, and outwardly extending from said flat member in its operative guard position to act as a support for working implements, a spring controlled latch co-operating with the said platform to lock the flat member in its inoperative position, and a loop pivoted to the sides of said flat member and a recessed member on top of said stepladder, said recessed member co-operating with said loop to act as a locking member for the guard in its upwardly extended position, the recess in said member presenting a fingerhold for engaging said loop to turn the same about its pivots for releasing the locking position of the loop and allowing a return of the flat member into its inoperative position.

2. A stepladder attachment comprising a substantially flat member attached to one member of the stepladder to fold flat against the same, means to lock the said attachment in its folded position, and means to lock said attachment in its unfolded upright position when acting as a

safety device, said last named means comprising a recessed member on top of the stepladder, and a loop pivotally attached with its ends to the said flat member and engaging said recessed member in the upright position of the flat member while said recess presents a fingerhold to disengage the loop from said recessed member to allow the flat member to assume its inoperative position.

3. In a stepladder as described a safety device hingedly connected at its upper end to the stepladder supporting legs, a platform attached to the lower end of said safety device, and an auxiliary curved member on the inner face of said platform, a housing secured to the lower part of one stepladder leg above said platform, and a spring controlled latch in said housing adapted to ride over said auxiliary member and engage the platform behind the same to operatively lock the safety device in its inoperative position folded against the ladder part, said platform in the operative position of the safety device when swung about its hinge into upright position extending above the upper end of the stepladder to act as a support for working implements, and a loop having angular ends engaging the side edges of said safety device and pivoted thereto, a recessed member attached to the uppermost platform of the stepladder to be engaged by said loop to lock the safety device in its operative position to act as a guard for preventing a person standing on said ladder platform from toppling forward, said loop to be operated by a finger passed through the recess of said platform member to release the loop from its engagement of said recessed member and allow a turning of said safety device about its hinges to assume a position flat against one member of the stepladder for storing when said stepladder is collapsed, and means to movably limit the distance between the members of said stepladder.

WILLIAM MUMBRAUER.
